METHOD OF FLUIDIZATION

Gino P. Giusti, New Kensington, and Axel R. Johnson, Pittsburgh, Pa., assignors to Texas Gulf Sulphur Company, New York, N. Y., a corporation of Texas

Application June 26, 1952, Serial No. 295,746

5 Claims. (Cl. 75—9)

This invention relates to a fluidization process involving a gas and an ore or other solid in which the gas may react chemically with the ore or other solid or may act physically on the ore or other solid.

In the fluidization technique a minimum gas velocity is required to maintain the bed of solids in the desired fluidized state. This minimum gas velocity is a complex function of the properties of the fluidizing gas and the size and shape of the solid being fluidized. For a given material higher gas velocity is required for a larger particle than for a smaller one. Present practice in industrial units is to supply the solids at a maximum particle size of 14 mesh because the use of particles of much larger size requires such high gas velocities, with attendant increased cost, as to be uneconomical. That is due to the fact that a major cost item in a fluidization process is that of grinding the material to a size amenable to fluidization at an economical gas velocity, i. e., the higher the velocity the greater the cost of developing it.

It is among the objects of this invention to provide a method and apparatus for fluidized treatment of a solid material with a gas that makes use of the characteristic of some ores and other solids to disintegrate into finer particles when heated, that permits the direct feeding of the solid material in the form of much coarser particles than has heretofore been practicable in the fluidization technique, that avoids the necessity of grinding the solid to readily fluidizable particle size, and that effects the desired result as readily and efficiently as would be the case if the solid were fed in the conventional finely divided form.

A particular object is to provide a method of treating certain sulfur ores that disintegrate due to chemical or physical action under the influence of heat while obtaining the advantages stated in the foregoing object.

A further object is to provide a method in accordance with the foregoing objects in which there is exothermic chemical reaction between the solid and the fluidizing gas.

A further object is to provide simple apparatus for performing the method.

Other objects will appear from the following specification.

The invention will be described with reference to the accompanying drawings in which Fig. 1 is a schematic representation of one form of apparatus in accordance with and for practicing the method of the invention; and Fig. 2 a fragmentary view similar to Fig. 1 showing a modified embodiment.

We have discovered, and it is upon this that our invention is in large part predicated, that in the fluidization technique of conducting a process involving a gas and a solid, typified by an ore, an unusually coarse ore feed may be used where the ore is of the type that disintegrates upon being heated. More particularly, in the practice of our invention such an ore in the form of lumps too large to be fluidized practically and economically if not heat-

2

disintegrable is fed to a fluidized bed in which the ore reacts chemically with the fluidizing gas with liberation of heat or physically, due to the heat in the gases, giving off gaseous products. Under the influence of heat within the fluidized bed the coarse ore particles disintegrate largely or wholly into particles fine enough for ready fluidization by the conventional gas velocities.

The importance of eliminating part of the grinding to fine particles becomes evident upon consideration of Ritter's Law, the validity of which, at least in the range of small particle sizes, has been confirmed by the work of the U. S. Bureau of Mines reported in its Bulletin 402. That law states that the work required for size reduction in grain is proportional to the new surface area formed. Assuming, for simplicity, that the particles being ground are spheres, a plant grinding ore 5 inches in diameter to $\frac{1}{2}$ inch diameter will use only about one-half the power required to reduce the same size feed to minus 14 mesh. Consequently it is clear that in the practice of this invention major savings are attained by the ability to use a coarser feed than has been conventional.

In the practice of this invention the coarse ore is fed, say as $\frac{1}{2}$ inch lumps, to a fluidized bed in a shaft having at its lower end a conduit of substantially smaller cross sectional area to which the fluidizing gas is supplied. The cross sectional area of the shaft and of its downwardly extending conduit are so related to each other and to the velocity of the gas supplied to the conduit that the velocity within the conduit is sufficient to keep the bed in the shaft but such that due to the increased cross sectional area in the shaft the consequent lowered velocity suffices to fluidize the bed.

The large ore particles fed to the bed disintegrate, or shatter, upon contact with or moving through the bed due to heat in the fluidized bed so that all, or substantially all, of the ore feed disintegrates into readily fluidized size. Any material that does not so disintegrate eventually reaches and leaves the bottom of the bed through the conduit and such over-size material is withdrawn in any of a variety of ways. The disintegrated material, or cinder, is continuously withdrawn from the upper surface of the bed to maintain a substantially constant upper bed level. Due to the retarded movement through the bed, such over-size particles will have been largely reacted before they drop from the bed. Likewise, product gases are withdrawn from the bed and treated in accordance with the reaction products and the ultimate products desired.

In the practice of the invention the heat in the bed may be supplied by exothermic reaction between the ore and the fluidizing gas or it may be supplied by burning a combustible gas in the bed or by fluidizing with heated inert gas. For example, in the case of disintegrable sulfur ores fluidizing with hot inert gas will effect the desired disintegration and at the same time cause distillation of sulfur from the ore. Or, various chemical reactions may be accomplished, as by fluidizing with air under conditions to cause combustion of part or all of the sulfur to sulfur dioxide with liberation of the heat necessary to cause physical disintegration of the coarse feed. Again, chlorine will react with elemental sulfur or sulfide sulfur in ores. Likewise, although the invention is typified by and explained with reference to certain sulfur ores, it is applicable likewise to other solids that disintegrate under the influence of heat or by reaction.

The invention may be described in further detail with reference to the accompanying drawings. Having reference to Fig. 1 there is provided a shaft 1 for receiving a fluidized bed 2. At its lower end the shaft slopes downwardly and inwardly and terminates in a cylindrical conduit 3 of

substantially smaller cross sectional area than that of shaft 1. In this embodiment conduit 3 extends into a chamber 4. Gas for fluidizing is supplied to the chamber through a conduit 5.

In accordance with the invention the gas is supplied at a velocity such as to be great enough in conduit 3 to maintain the fluidized bed 2 within the shaft, thus eliminating the bed plate that supports the fluidized bed in conventional fluidizing apparatus and which would, if used permit the build up of over-size solids and eventually halt fluidization. In other words, the shaft is freely open to its downward continuation portions.

For most purposes the cross sectional area of conduit 3 is but a fraction of that of the shaft 1, its exact area being dependent upon the velocity of the gas passing upwardly through it and the character and depth of the bed so as to hold the bed within the shaft but at the same time so that the velocity of the gas when it expands into the shaft, and thus flows at a lower velocity, will fluidize the bed. Preferably the relations are such that, for many purposes, the velocity in the bed is from 0.5 to 2.0 feet per second. For most purposes it is preferred that the velocity within the shaft shall be below the minimum carry-over velocity of the bed and treated ore, or cinder, particles although if desired for any reason it can be such as to cause complete, or substantially complete, carry-over of cinder with the product gases.

The ore is fed continuously to shaft 1, as by appropriate feeding means, not shown, to a conduit 6 so that the coarse particles fall to the upper surface of bed 2. In accordance with the invention the ore feed contains particles so coarse, e. g., one-half inch lumps, as to be not fluidizable under the gas velocities normally used in fluidizing, e. g., 0.5 to 2.0 feet per second. As the ore enters the bed it becomes heated and disintegrates into sizes adapted to fluidization, say 14 mesh or finer. The treated ore is removed to maintain the upper bed level by any suitable means, as by means of an over flow 7. Product gases are withdrawn from the top of the shaft through a conduit 8 and treated according to the operation being conducted.

Any coarse ore particles that are not disintegrated to fluidizable size will eventually work to the bottom of the bed under the fluidizing action and will fall through conduit 3 into chamber 4 from which they may be removed periodically or continuously by the use of any suitable valving means 9 that does not interfere with the fluidizing.

The invention is particularly applicable to the treatment of certain sulfur ores that are found in surface deposits in Peru and Chile and which, when dropped into a bed supplied with air, will under the resultant combustion fall apart into particles readily fluidizable, leaving only about 10 percent, and not more than about 20 percent, of the feed in lumps too large for fluidization. Such ores carry sulfur mechanically rather than chemically bound, and usually they are of siliceous nature. In other words, in such ores the sulfur is free as contrasted with that in pyrites. Alternatively, these same ores will disintegrate when dropped into a bed supplied with a burning gas or with hot, inert gases.

In the bed, assuming air as the fluidizing gas, at least some of the sulfur of the ore will be burned to sulfur dioxide, and the product gases composed of sulfur vapor, sulfur dioxide and nitrogen, are withdrawn and treated to recover the sulfur and possibly the sulfur dioxide, which may be recovered as such or used for the production of elemental sulfur. If the fluidizing gas in either a burning gaseous fuel or hot, inert gases, then the product gases composed of sulfur vapor and inert constituents are withdrawn and treated to recover the sulfur. Depending upon the ore and upon the conditions within the bed, such as volume of air feed, the product gases may contain sulfur dioxide and no sulfur vapor.

In starting up a bed, ore of minus 14 mesh may first

be supplied to form an original bed that is fluidized by air to supply heat, or by other gas, the main purpose being to bring the bed to a temperature sufficient to cause disintegration of coarse particles as charged and to be able to continue operation in this manner. When the bed has reached the proper temperature the feed of fine material is discontinued and thereafter the ore is fed in the coarse form characteristic of this invention. Alternatively, if desired for any purpose, the bed may be formed initially from an inert material that is brought to heat in any desired way, as by means of gas burners, after which the coarse ore feed is initiated and continued. Various inert materials may be used for this purpose, an example being firebrick of 20 x 60 mesh size.

The embodiment shown in Fig. 2 differs from that of Fig. 1 in that the fluidizing gas is supplied through a conduit 5a directly to the conduit 3a that extends downwardly from the shaft 1a, and at its lower end the conduit 3a opens into a collecting chamber 10 from which the accumulated over-size particles are withdrawn through suitable valving means 9a.

Although in the embodiments shown the ore is fed above the surface of the fluidized bed, it will be understood that it can likewise be fed directly into the bed, e. g., laterally or sub-surface.

In view of what has been said the term "reacting" as used in the claims is to be taken to include both true chemical reaction accompanied by disintegration to smaller particle size as well as the physical reaction of disintegration unaccompanied by chemical action. Likewise, the term "ore" is used to refer to solids that are disintegrable by heat or by reaction.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. In a fluid bed method of reacting a gas and an ore, the steps comprising providing said bed in a shaft freely open to a downwardly extending continuation of substantially smaller cross sectional area that is freely open to a receiving chamber, continuously passing gas reactive with said ore into said continuation at a velocity therein to maintain said bed in said shaft but by the resultant decreased velocity upon entering the shaft to fluidize the bed, continuously feeding to said bed ore disintegrable by heat in the form of lumps too large to be fluidized and supplying heat in the bed to disintegrate such lumps into particles of fluidizable size, any oversize ore as it reaches said continuation falling freely through it, against the upflow of said gas therein, into said chamber, withdrawing oversize material from said chamber, withdrawing treated ore of fluidizable size from the upper end of said bed, and withdrawing gases from the bed.

2. A method according to claim 1 in which the said bed is fluidized below the minimum carry-over velocity of the treated ore.

3. A method according to claim 1 in which said ore is a sulfur ore, and said gas is air.

4. A method according to claim 1 in which the heat in the bed is supplied by reaction between the ore and the gas.

5. A method according to claim 4 in which the ore is a sulfur ore carrying mechanically bound sulfur, and the gas is air.
